UNITED STATES PATENT OFFICE.

BERNDHART L. WESSELS, OF WOODHAVEN, NEW YORK.

WIRE-FENCE ANCHORING AND SUPPORTING STAKE.

1,345,650.

Specification of Letters Patent.

Patented July 6, 1920.

Application filed September 1, 1917. Serial No. 189,282.

To all whom it may concern:

Be it known that I, BERNDHART L. WESSELS, a citizen of the United States of America, and resident of Woodhaven, Long Island, State of New York, have invented certain new and useful Improvements in Wire-Fence Anchoring and Supporting Stakes, of which the following is a specification.

10 This invention relates to a drivable self anchoring upright fence stay adapted to engage the wires of a wire fence and having sufficient stability and rigidity to aid in maintaining the fence in position.

15 Figure 1 of the accompanying drawings represents a perspective view of this improved fence stay.

Fig. 2 represents a side elevation of a wire fence having a series of these fence stays embodied therein.

Fig. 3 represents a transverse vertical section of said fence on line 3—3 of Fig. 2.

Fig. 4 represents a side elevation of another form of fence in which these stays are employed.

The same reference numbers indicate corresponding parts in the different figures.

This drivable self anchoring stable fence stay comprises a driving solid head 11 and two straight parallel rigid bars 12 and 13 united at their upper ends with said head, and spaced apart forming a slot *o* between them about the width of a wire fence. These stiff or rigid bars are provided at their lower ends with broad beveled blades 14 disposed parallel with the slot *o* between them. The lower portions of said bars 12 and 13 are each provided on their outer faces above said blades with a vertical series of wedge teeth 15 in parallel relation with said blades. Owing to the substantial construction of the stay as aforesaid, when driven into place it is firmly anchored in the ground by its stiff straight toothed lower portions and stands upright in its upper portion, said upper portion forming in conjunction with said anchored lower portions a stable brace or support above the surface of the ground, which prevents the fence from falling to either side.

In the use of this device, the stay 10 is made to straddle several wires of the fence and driven by blows on its driving head 11 into the ground. If desired several of the

stays at suitable distances apart may be 55 made to engage only the lowermost wire as at 18. The stays so driven are principally for anchoring while the others form both anchors and supports.

In Fig. 4, I have shown the application 60 of my invention to a slightly modified form of fence, in which the wicket portions 19 are held together by interlocking rings 20 at the lower portion thereof. The supporting and anchoring stakes are engaged over the upper edge of the rings 20 as at 21, while those employed principally for anchoring are as at 22 engaged over the lower portion of the rings 21.

It will be understood that my invention 70 may be used with other forms of fences, and also for guy wires, tent ropes, and other similar uses which will be apparent. My improved device is simple and inexpensive in construction, and will form an effective 75 and reliable means for supporting and anchoring fences.

I have illustrated preferred and satisfactory forms of my invention, but it is obvious that changes may be made therein within 80 the spirit and scope thereof, as defined in the appended claim.

I claim:

An article of manufacture consisting of an upright anchoring drivable fence stay 85 for a wire fence composed of a driving solid head and two straight parallel rigid bars spaced apart the width of a fence wire, integrally united at their upper ends with said head and provided at their lower ends 90 with broad beveled blades disposed parallel with said space, the upper portion of said stay being adapted to hold in said slot a series of fence wires and the lower portion thereof being adapted to be driven into the 95 earth and serve as an upright anchor for the stay, said lower portion being provided on the outer faces of its bars with a vertical series of wedge-like teeth in parallel relation with said blades.

100 In testimony, that I claim the foregoing as my invention, I have signed my name in presence of two subscribing witnesses.

BERNDHART L. WESSELS.

Witnesses:

H. N. STUART,
MOE M. WEINBERG.
